UNITED STATES PATENT OFFICE.

JOHN TAYLOR, OF PHILADELPHIA, PENNSYLVANIA.

DESIGN FOR KNITTED NUBIA FABRIC.

Specification forming part of Design No. 5,283, dated September 26, 1871.

To all whom it may concern:

Be it known that I, JOHN TAYLOR, of Philadelphia, county of Philadelphia, State of Pennsylvania, have invented or produced a Design for a Knitted Nubia Fabric, of which the following is a specification:

The figure in the accompanying drawings represents sufficient of a knitted nubia fabric to illustrate my design, which consists in the combination of a fringe, A, of the character clearly shown in the drawings, with a body, B, of a different fabric, knitted more closely, so as to be suitable for the body of a nubia.

I claim—

The design for a knitted nubia fabric, in which are combined a fringe, A, and a body, B, of a different fabric.

In testimony whereof I have signed my name to this specification in the presence of two subscribing witnesses.

JOHN TAYLOR.

Witnesses:

Wm. A. STEEL,
HARRY SMITH.
